G. CLAUSING

LAST

Filed April 27, 1925

INVENTOR
GEORGE CLAUSING,

By *Toulmin Toulmin*,

ATTORNEYS.

UNITED STATES PATENT OFFICE.

GEORGE CLAUSING, OF PORTSMOUTH, OHIO, ASSIGNOR TO THE VULCAN LAST COMPANY, OF PORTSMOUTH, OHIO, A CORPORATION OF OHIO.

LAST.

Application filed April 27, 1925. Serial No. 26,034.

To all whom it may concern:

Be it known that I, GEORGE CLAUSING, a citizen of the United States, residing at Portsmouth, in the county of Scioto and State of Ohio, have invented certain new and useful Improvements in Lasts, of which the following is a specification, reference being had therein to the accompanying drawing.

10. My invention relates to lasts.

It is the object of my invention to provide a last which will be yieldingly held in its expanding or collapsed position.

It is a further object of my invention to 15 provide a last having a resilient lever and link for the dual purpose of connecting the parts so that a line drawn between the centers of the ends of the link will pass over the dead center of movement of the last parts 20 and through the leverage of the link of the spring lever flex the spring.

It is my object to provide a link which is anchored to a last part at one end and to the spring lever at the other so arranged that 25 the pivotal mounting of the link and the pivotal mounting of the lever on the last parts will not have the line drawn between their centers pass over the center of movement of the last parts.

30. It is a further object to have the pivotal point of support of the link so arranged that a line drawn between the centers there, of will pass over the center of movement of the last parts, one end of the link being 35 mounted upon the spring lever.

Referring to the drawings:

Figure 1 is a side elevation partially in section of a last with the link and spring lever construction of my invention;

40. Figure 2 is a plan view of the link and spring construction with the anchor pins partially broken away.

Referring to the drawings in detail, 1 is the toe part of a last having a cut away or 45 slotted portion 2 for receiving the spring and links. The rear face of this last half is designated 3. The surface is flat save for the exception of a transverse semicircular groove 4 for receiving a transverse cylindrical shoulder 5 of the heel part 6. This heel part is provided with a cut away slot 7. An abutment pin 8 is provided in this projecting shoulder 5, the center of the pin 8 being located on the center of movement of 50 the last parts. The forward face 9 of the

rear half of the last is cut away to permit of the last collapsing.

In the rear last half near the bottom thereof and transversing the slot 7 is an anchor pin 10. Mounted on this anchor pin 60 are arched shaped links 11. The other end of these links is pivoted on a stud 12 which is carried by the spring lever which consists of a lever portion 13 pivoted on an anchor pin 14 at one end and to the links 11 at 65 the other. This spring lever is provided with a spring arm which is arch shaped proceeding approximately 90 degrees from the point of pivotal connection of the link to the spring lever to a point where it projects through the front last half into the rear last half, this part being marked 15. The rear end of this part 15 passes downwardly at 16 and then forwardly at 17 parallel to a space over the part 15 and then 70 terminates in a hook 18 which is hooked over the abutment pin 8.

It will be observed, therefore, that a line drawn between the centers of the anchor pins 10 and 14 will never pass over the 75 center of the pin 8 and that a line drawn between centers of the pin 10 and 12 will pass over the center of the pin 8.

It will be understood that I desire to comprehend within my invention such modifications as may be necessary to adapt it to varying conditions of use.

Having thus fully described by invention, what I claim as new and desire to secure by Letters Patent, is:

1. In a last, a toe part and a heel part adapted to move one on the other, a link joining said parts, a spring lever pivoted on one of said parts and engaging the other of said parts, one end of said link being pivoted on said spring lever and the other pivoted on another last part than that associated with its point of pivotal connection with the spring lever, and an abutment pin carried by one of said last parts against which the end of the spring lever engages.

2. In a last, a toe part, a heel part, a link connecting said parts, a spring lever pivoted on one of said parts, said link being pivoted thereto at a point remote from the pivotal mounting of the spring lever, and an abutment pin carried by one of said last parts against which the end of the spring lever engages.

3. In a last having a toe part and heel

part adapted to rock one on the other, an abutment pin located on the center of their movement, a link connecting said parts, one end of the link being pivoted on one last part and the other end being pivoted on a spring lever, a spring lever, means of pivotally supporting said spring lever on the other last parts, the free end of the spring lever abutting with the abutment pin.

10 4. In a last having a toe part and heel part adapted to rock one on the other, an abutment pin located on the center of their movement, a link connecting said parts, one end of the link being pivoted on one last part and the other end being pivoted on a spring lever, a spring lever, means of pivotally supporting said spring lever on the other last parts, the free end of the spring lever abutting with the abutment pin, the 15 pivotal point of connection of the link with one last part and with the spring lever being so arranged that a line drawn between the centers of said pivotal points will pass over the center of the abutment pin when the 20 parts are moved from one position to the other.

5. In a last having a toe part and heel part adapted to rock one on the other, an abutment pin located on the center of their 30 movement, a link connecting said parts, one end of the link being pivoted on one last part and the other end being pivoted on a spring lever, a spring lever, means of pivotally supporting said spring lever on the other last parts, the free end of the spring 35 lever abutting with the abutment pin, the pivotal point of connection of the link with one last part and with the spring lever being so arranged that a line drawn between the centers of said pivotal points will pass over the center of the abutment pin when the parts are moved from one position to the other, and a line drawn between the pivotal point of connection of the link with the 40 last part and the pivotal point of connection of the spring lever with the other last part will never pass over the center of the abutment pin.

6. In a last, a toe part, a heel part adapted to rock one on another, an abutment carried by one of said parts, a link joining said parts, a spring lever consisting of a lever arm and a spring member engaging with said abutment, means of pivotally mounting the lever end of the spring lever in one of the last parts, said spring lever being so arranged that at its spring end it doubles back upon itself in a U-shaped end terminating in a hook engaging with the abutment.

60 7. In a last, a toe part, and a heel part adapted to rock upon one another with a knuckle joint, an abutment pin in said knuckle joint, a lever pivoted in one part of the last having a quadrant shaped spring arm projected at right angles thereto and

terminating in a U-shaped end with a hook engaging said abutment, a link pivoted on said lever at one end and on the other last part at the other end.

8. In a last, a toe part, and a heel part 70 adapted to rock upon one another with a knuckle joint, an abutment pin under said knuckle joint, a lever pivoted in one part of the last having a quadrant shaped spring arm projected at right angles thereto and 75 terminating in a U-shaped end with a hook engaging said abutment, a link pivoted on said lever at one end and on the other last part at the other end, said link being arched to clear the abutment pin.

9. In a last, a toe part, a heel part adapted to rock one on the other, a pair of links connecting said parts to one another, the ends of the links on one side being mounted on an anchor pin in one last part 80 and upon a spring lever within the other last part, means of pivotally mounting said lever in said last part last mentioned between said links, said spring lever having its free end engaging with an abutment pin, 85 and an abutment pin, said spring lever consisting of a lever portion extending from the point of its pivotal connection in the last part to its point of pivotal connection to the forward end of the links, and a spring 90 lever part extending in a quadrant from one last part to a point within the other last part.

10. In a last, a toe part, a heel part 100 adapted to rock one on the other, a pair of links connecting said parts to one another, the ends of the links on one side being mounted on an anchor pin in one last part and upon a spring lever within the other last part, means of pivotally mounting said lever in said last part last mentioned between said links, said spring lever having its free end engaging with an abutment pin, 105 and an abutment pin, said spring lever consisting of a lever portion extending from the point of its pivotal connection in the last part to its point of pivotal connection to the forward end of the links, and a spring 110 lever part extending in a quadrant from one last part to a point within the other last part, and then turning upon itself to form a U-shaped end, the other end of which terminates in a hook over said abutment pin.

11. In a last, a toe part and heel part, a knuckle joint, arch shaped links pivoted on the anchor pin to the heel part and upon the spring lever in the toe part, an anchor pin in the toe part for pivotally supporting said spring lever, a spring lever having a lever portion, and an arch shaped spring portion 120 located between said links, an abutment pin within the arch of the arch shaped links, and a U-shaped hook end of the spring lever engaging with said abutment pin.

12. In a last, a toe part and heel part, a 125

knuckle joint, arch shaped links pivoted on the anchor pin to the heel part and upon the spring lever in the toe part, an anchor pin in the toe part for pivotally supporting said 5 spring lever, a spring lever having a lever portion, an arch shaped spring portion located between said links, an abutment hook pin within the arch of the arch shaped links, and a U-shaped hook end of the spring 10 lever engaging with said abutment pin, the points of connection of the links with the heel part and the point of connection of the spring lever with the toe part being so arranged that a line drawn between their centers 15 will not pass over the center of movement of the last parts.

13. In a last, a toe part and heel part, a knuckle joint, arch shaped links pivoted on the anchor pin to the heel part and upon the 20 spring lever in the toe part, an anchor pin in the toe part for pivotally supporting

said spring lever, a spring lever having a lever portion, an arch shaped spring portion located between said links, an abutment hook pin within the arch of the arch shaped links, 25 and a U-shaped hook end of the spring lever engaging with said abutment pin, the points of connection of the spring lever with the toe part and the points of connection of the links with the heel part being so arranged 30 that a line drawn between their centers will not pass over the center of movement of the last parts, and that a line drawn between the center of connection of the links with the heel part to the pivotal center of connection of the links with the spring lever will pass over such center point of the abutment pin when the parts are moved from one position to another. 35

In testimony whereof, I affix my signature.

GEORGE CLAUSING
